CLAIM

The ornamental design for a wand vacuum assembly, as
shown and described.

DESCRIPTION

FIG. 1 is a front view of another example of a wand vacuum
assembly showing the claimed design;

FIG. 2 is a rear view of the wand vacuum assembly of FIG.
1;

FIG. 3 is a top view of the wand vacuum assembly of FIG.
1;

FIG. 4 is a bottom view of the wand vacuum assembly of
FIG. 1;

FIG. 5 is a left view of the wand vacuum assembly of FIG.
1;

FIG. 6 is a right view of the wand vacuum assembly of FIG.
1;

FIG. 7 is a perspective front, top, right of the wand vacuum
assembly of FIG. 1;

FIG. 8 is a perspective front, top, left of the wand vacuum
assembly of FIG. 1;

FIG. 9 is a perspective rear, top, right of the wand vacuum
assembly of FIG. 1;

FIG. 10 is a perspective rear, top, left of the wand vacuum
assembly of FIG. 1;

FIG. 11 is a perspective front, bottom, right of the wand
vacuum assembly of FIG. 1;

FIG. 12 is a perspective front, bottom, left of the wand
vacuum assembly of FIG. 1;

FIG. 13 is a perspective rear, bottom, right of the wand
vacuum assembly of FIG. 1; and,

FIG. 14 is a perspective rear, bottom, left of the wand
vacuum assembly of FIG. 1.

The broken lines in the drawings depict unclaimed subject
matter that forms no part of the claimed design.
